UNITED STATES PATENT OFFICE.

CHARLES WINKLER, OF SAN ANGELO, TEXAS.

TAG.

SPECIFICATION forming part of Letters Patent No. 535,876, dated March 19, 1895.

Application filed December 7, 1893. Serial No. 493,059. (No model.)

To all whom it may concern:

Be it known that I, CHARLES WINKLER, a citizen of the United States, residing at San Angelo, in the county of Tom Green and State of Texas, have invented a new and useful Tag, of which the following is a specification.

My invention relates to improvements in tags, and especially to that class thereof employed for marking dry-goods.

10 The objects of my invention are to produce a cheap and simple tag, and more particularly a convenient means for fastening the same in such position upon a bolt of goods as to prevent it from becoming twisted or turned, and 15 so that the tag will always be held or supported so as to exhibit the markings thereon.

With these and other objects in view the invention consists in the hereinafter described tag and fastener.

20 Referring to the drawings:—Figure 1 is a perspective view of one end of a bolt of goods, the same having secured thereto a tag embodying my invention. Fig. 2 is a longitudinal sectional view of the two inner laminals 25 or layers of goods, the same having the interposed tag. Fig. 3 is a detail of the tag before applying the fastener. Fig. 4 is a detail of the fastener before bending. Fig. 5 is a perspective view of the tag after the application 30 of the fastener. Fig. 6 is a reverse view of the same.

Like numerals of reference indicate like parts in all the figures of the drawings.

In constructing the tag I employ an oblong 35 blank of suitable fabric or material, the same being of a stiff nature, and bend the same between its ends at 1 and 2, forming the intermediate portion 3 and the long and short end flaps 4 and 5 respectively. The flap 4 is folded 40 over on the line 1 upon the intermediate portion 3, after which the short flap 5 is folded upon the flap 4. This completes the tag, and the same may have its external surface provided with any desired printing as will be 45 obvious.

The fastener is formed of metal and in one piece and has a general T-shape, in that it consists of the upper transverse bar 6, the opposite end-tongues 7, and the intermediate 50 longer tongue 8, each of the tongues terminating in piercing-points. The three tongues are passed through the flaps 4 and 5 and the portion 3 of the tag, and the intermediate tongue 8 bent backward to the opposite side of 55 the tag, so that as will be obvious we have on

one side of the tag two tongues 7 and on the opposite side the single tongue 8. The tag is now in condition to be placed in the bolt, and is slipped endwise between two laminals or layers adjacent to the center of the bolt; a forward pull on the tag serves to enter the points in the goods, so that the tag will become fastened at each side and at the three points, hence preventing any permanent turning of the tag, and in fact any turning whatever, except such that may be permitted by reason of the flexible nature of the tag. In this manner the tag is permanently supported in position for reading, so that the marks thereon are constantly presented to the view of the salesman.

From the foregoing description in connection with the accompanying drawings, it will be seen that I have provided a very simple and efficient tag and tag-fastener, the same 75 being readily applied to position, secure, and always maintained in proper position.

Having described my invention, what I claim is—

1. A tag, combined with the tag fastener, 80 having a general T-shape, and comprising the cross-piece 6 arranged transversely of the tag adjacent to one end thereof, the end tongues, and the intermediate tongue, all three tongues being passed through the tag, and arranged 85 at an angle thereto, the end tongues being located at one side of the tag and the intermediate tongue being arranged at the other side and being bent over the end of the tag and crossing the cross-piece, substantially as 90 and for the purpose described.

2. The tag comprising the intermediate body-portion 3, and long and short end flaps 4 and 5 overlapping said body-portion, combined with the T-shaped fastener formed of a 95 single piece of metal and comprising the cross-bar 6, end tongues 7, and intermediate tongue 8, the three tongues being passed through the flaps and body-portion of the tag, and the intermediate tongue being bent over upon the 100 upper end of the tag to the opposite side thereof, substantially as specified.

In testimony that I claim the foregoing as my own I have hereto affixed my signature in the presence of two witnesses.

CHARLES WINKLER.
